UNITED STATES PATENT OFFICE.

ALLAN J. BARBER, OF WOONSOCKET, RHODE ISLAND.

DRAWING-FRAME.

1,255,074.

Specification of Letters Patent. Patented Jan. 29, 1918.

Application filed February 9, 1917. Serial No. 147,577.

To all whom it may concern:

Be it known that I, ALLAN J. BARBER, a citizen of the United States, and a resident of Woonsocket, in the county of Providence and State of Rhode Island, have invented 5 a new and Improved Drawing-Frame, of which the following is a full, clear, and exact description.

My invention has for its object to provide 10 a drawing frame having a body on which a pattern may be disposed with a piece of transparent paper extending over the pattern, improved means being provided for securing the transparent paper to the body 15 and for bending the body to stretch the paper over the body and the pattern.

Additional objects of the invention will appear in the following specification in which the preferred form of the invention 20 is disclosed.

In the drawings similar reference characters denote similar parts in all the views, in which—

Figure 1 is a perspective view illustrating 25 the invention;

Fig. 2 is an inverted plan view of the drawing frame illustrated in Fig. 1;

Fig. 3 is a side elevation of the drawing frame before the body has been bent;

Fig. 4 is a view similar to that shown in Fig. 3, but illustrating the position of the body when it is bent to stretch the paper; and

Fig. 5 is a side elevation of a modified 35 form of the invention.

By referring to the drawings, it will be seen that a resilient body 10 is provided, the ends 11 of which are curved downwardly, outwardly and upwardly to form 40 transverse grooves 12. When using the drawing frame, a pattern 13 is disposed on the body 10, and over this pattern 13 is disposed a piece of transparent paper 14, the ends of which extend to the transverse 45 grooves 12. When this has been done, one of the rollers 15 is moved along the piece of transparent paper to one of the grooves 12, and the paper at the said groove 12 is forced into the groove by means of the said 50 roller, the roller seating on portions 16 of the body which are cut and bent upwardly at the transverse grooves 12. The other roller 15 is then moved from the first mentioned roller, over the piece of transparent 55 paper 13 in the direction of the other groove

to smooth the transparent paper, the piece of transparent paper being secured at the other groove by pressing the last mentioned roller into the said groove and against the portions 16 of the body which serve as a 60 seat. By this means the piece of transparent paper is secured to the body 10 with the pattern 13 disposed under the piece of transparent paper. The piece of transparent paper is then stretched over the upper face 65 of the body 10, and is pressed against the pattern 13 and the body 10 by bending the ends of the body downwardly, thereby making the upper surface of the body convex. In order to bend the ends 11 of the body 70 downwardly, the body at one of the transverse grooves 12 is cut to form a flange 17, and the body at the other transverse groove is cut to form a flange 18, a tie member 19 being secured to the flange 17, and this tie 75 member being secured to a lever 20 which is fulcrumed at 21 to the flange 18. When the lever 20 is disposed substantially as shown in the dotted lines in Fig. 2 of the drawings, the body 10, which is constructed of a 80 resilient material, is substantially flat, but when the lever 20 is moved to the position illustrated by the full lines in Fig. 2 of the drawings, the body 10 is curved as illustrated in Fig. 1 of the drawings. There is 85 a catch 22 on the body which serves to hold the lever 20 in the position illustrated by the full lines in Fig. 2 of the drawings.

Fig. 5 of the drawings illustrates a modified form of the invention, in which a rigid 90 body 10^a is provided, having a convex upper surface. The ends of the body 10^a are bent downwardly, outwardly and upwardly, as at 12^a to form transverse grooves in which the rollers 15 may seat against the ends of 95 the piece of transparent paper 14. The sides 23 of the body 10^a extend downwardly, and the body 10^a beyond the transverse grooves 12^a also extend downwardly at 24 to form with the sides of the body 10^a supporting 100 members.

By stretching the paper over and tightly against the pattern in the manner described, a heavier and better quality of paper may be used than is the case where the paper is 105 stretched flat over the pattern.

Having thus described my invention, I claim as new and desire to secure by Letters Patent:

1. In a drawing frame, a body curved 110

from its middle portion downwardly and in the direction of opposite ends, the body at its ends being bent downwardly, outwardly and upwardly to form two transverse 5 grooves, and two members for pressing a paper over the convex upper surface of the body and the ends of the paper into the grooves.

2. In a drawing frame, a resilient body 10 having opposite ends bent downwardly, outwardly and upwardly to form transverse grooves, two members for pressing a paper over the upper surface of the body and the ends of the paper into the grooves, and 15 means for bending the body between its ends to present a convex upper surface.

3. In a drawing frame, a resilient body, means to secure a piece of paper to the upper surface of the body, a tie member secured to the under surface of one end of the body, a lever secured to the under surface of the other end of the body, the tie member being secured to the lever so that a movement of the lever will draw the ends of the

body in the direction of each other to curve 25 the upper surface of the body.

4. In a drawing frame, a resilient body, means to secure a piece of paper to the upper surface of the body, and means disposed under the body and connecting the ends of 30 the body to draw the ends of the body in the direction of each other to give the body a convex upper surface.

5. In a drawing frame, a resilient body having opposite ends bent downwardly, outwardly and upwardly to form transverse 35 grooves, two members for pressing a piece of paper against the upper surface of the body and the ends of the paper into the grooves, a tie member secured to the under 40 surface of one end of the body, a lever secured to the under surface of the other end of the body, the tie member being secured to the lever so that a movement of the lever will draw the ends of the body in the direction of each other to curve the upper surface 45 of the body.

ALLAN J. BARBER.
